(57) **CLAIM**

The ornamental design of an insert for packaging carton, as shown and described.

DESCRIPTION

FIG. 1 is a perspective view of an insert for packaging carton, showing our new design;

FIG. 2 is a front view thereof;

FIG. 3 is a back view thereof;

FIG. 4 is a right view thereof;

FIG. 5 is a left view thereof;

FIG. 6 is a top view thereof;

FIG. 7 is a bottom view thereof;

FIG. 8 is a perspective view of the insert for packaging carton, shown in a position of use with an exemplary packaging carton;

FIG. 9 is a front view thereof;

FIG. 10 is a back view thereof;

FIG. 11 is a right view thereof;

FIG. 12 is a left view thereof;

FIG. 13 is a top view thereof; and,

FIG. 14 is a bottom view thereof.

The broken lines are shown for the purpose of illustrating environmental subject matter of an exemplary packaging carton and form no part of the claimed design.
